SAFETY DEVICE FOR BURNERS

Ernest Riemenschneider, Detroit, Mich., assignor,
by decree of distribution, to Ernest Michael Rie-
menschneider, with National Bank of Jackson
as guardian

Application July 27, 1946, Serial No. 686,658

3 Claims. (Cl. 67—85)

1

This invention relates to burners or lamps, and more particularly to a safety device for a burner wherein means are provided for extinguishing the burner flame before it is possible to re-fuel the tank of the burner.

Heretofore there have been numerous accidents including fires and explosions due to re-fueling of the burner while there was still a flame on the burner wick.

The present invention has for its principal object the provision of a suitable cover or cap for the filler spout of the burner, together with means preventing its removal until the burner wick has been dropped down to its lowest position extinguishing the flame thereon.

It is the further object of this invention to provide means in conjunction with the filler spout of the fuel tank whereby it is impossible to elevate the burner wick without first replacing the cover of the fuel tank.

It is the further object of this invention to provide manually operable gear means for raising and lowering a novel cap which is slidably positioned within the filler spout of the lamp tank, together with gear means operated thereby which are joined to the conventional wick raising and lowering means whereby manual rotation of the cap operating gear means effects a corresponding, simultaneous operation in the opposite direction of the wick operating means.

It is the further object of this invention to provide a safety device for burners whereby the wick is lowered down into the lamp fully extinguishing the flame at the same time as the filler cap is upwardly elevated for removal.

These and other objects will be seen from the following specification and claims in conjunction with the appended drawing of which:

Fig. 1 is a top plan view of the burner showing the safety device.

Fig. 2 is an elevational section on line 2—2 of Fig. 1.

Fig. 3 is a fragmentary elevational section on line 3—3 of Fig. 1; and

Fig. 4 is a fragmentary top plan view of a slight variation of the safety device.

It will be understood that the above drawing illustrates merely a preferable embodiment of the invention and that other embodiments are contemplated within the scope of the claims hereafter set out.

Referring to the drawing, a burner is shown comprising a hollow doughnut shaped fluid tank 11, having a central hollow pedestal support 12

which projects upwardly therethrough as illustrated in Fig. 2.

Support 12, with a base 13, which is positioned below the bottom of tank 11, is centrally joined to the central portion of tank 11 by the 3 angularly arranged connecting struts 14. As shown in Fig. 1, struts 14 have a central base portion 15 which is suitably secured to the outside wall of support 12 in radially spaced relation.

The bifurcated portions of struts 14 extend downwardly, angularly, and their edges are suitably secured to inner wall 16 of tank 11 as by welding.

Solid cylindrical member 17 is centrally positioned within support 12 and rests upon base 13 with its outer walls concentrically spaced from the inner circular wall of support 12 providing the annular cylindrical recess 18.

Recess 18, extends the full length of support 12 and has positioned therein the annular hollow cylindrical fabric burner wick 19. The latter extends down into annular recess 18 and is immersed in the liquid fuel, such as kerosene, which is supplied to the bottom portion of recess 18 of support 12 by conduit 20, which extends from tank 11.

The fuel saturates the bottom portion of wick 19 and rises therein by capillary action to its upper surface where it may be ignited and burned 30 in the conventional manner.

Referring to Figs. 2 and 3, a sprocket gear 21 is secured upon the end of rotatable shaft 22 and positioned relative to wick 19 so that its teeth partially imbed therein. Consequently rotation 35 of gear 21 clockwise effects an upward translation of wick 19 within its cylindrical annular recess 18. Also counter-clockwise rotation of gear 21 effects a downward translation of said wick.

40 Hollow cylindrical fuel filling spout 23 extends down through an opening in the top surface of tank 11 and is secured thereto with its bottom portion being in spaced relation to the inner bottom surface of said tank as shown in Fig. 3.

45 A hollow cylindrical cap 24 is slidably and sealingly positioned within spout 23 and is adapted to vertical reciprocal movements therein. Cap 24 is open at its lower end and it is seen in the lowest position of cap 24, Fig. 3 that spout 23 is 50 entirely closed off from the interior of tank 11.

55 Rack gears 25 and 26 are positioned or formed upon opposite sides of cap 24 with gear 25 being in meshing engagement with sprocket gear 21 carried at the outer end of shaft 22 within housing 28,

A second sprocket gear 29 in housing 32 is secured on the end of manually rotatable shaft 30 having handle 31, and is operatively in mesh with rack gear 26 on cap 24.

To re-fuel tank 11 through spout 23 it is necessary to first remove cap 24 therefrom. This is accomplished by a clockwise rotation of handle 31 and gear 29 effecting elevation of said cap till it can be manually removed. At the same time that cap 24 is elevated it will be seen that wick 19 is effectively lowered so as to completely extinguish the flame at its top peripheral edge to thereby eliminate the hazard of explosion during the re-fueling operation.

Referring to Fig. 3, upward movement of cap 24 causes a counter-clockwise rotation of gear 27 which meshes with rack gear 25 on said cap. The movement of gear 27 is transmitted to gear 21 through shaft 22 whereby wick 19 is downwardly projected to or towards the bottom of opening 18 effectively extinguishing the flame. It is now safe to pour the fuel through spout 23 without danger of fire or explosion.

Furthermore, it will be seen that the wick can not be elevated for re-lighting until cap 24 is replaced and moved downwardly by a counter-clockwise rotation of handle 31 and gear 29.

Here again downward movement of cap 24 effects a clock-wise rotation of gear 27 with the latter effecting a corresponding clock-wise rotation of gear 21 to effectively elevate wick 19 to the proper height for igniting in the conventional manner.

It will be seen that tank 11 cannot possibly be refilled until wick 19 has been dropped to its lowest position and the flame thereon entirely extinguished. On the other hand, wick 19 cannot be re-ignited until the cap 24 is replaced within spout 23 and projected downwardly therein.

A slight variation of the safety device is illustrated in Fig. 4 wherein a sprocket gear 33 is carried at the outer end of wick operating shaft 22. Gear 33 meshes with rack gear 34, longitudinally carried on one side of tank cap 35.

A second sprocket gear 36 is carried on the inner end of shaft 37 which also meshes with rack gear 34 but is positioned in spaced relation to gear 33 for independent movement.

Manual rotation of shaft 37 by handle 38 is thus adapted to raise and lower cap 35. Here also it is seen that wick 19 will be at its lowest position when cap 35 is at its uppermost position of travel in spout 23 for removal for re-

fueling. Likewise wick 19 cannot be elevated for relighting until cap 35 is returned to its spout and lowered therein.

Having described my invention, reference 5 should now be had to the claims which follow for determining the scope thereof.

I claim:

1. A safety device for a burner having a fuel spout on its tank and rotatable wick raising and 10 lowering means comprising a removable cap reciprocally slidable within said spout, a pair of rack gears on opposite sides of said cap, a manually rotatable gear meshing with one of said rack gears to effect movement of said cap within said spout, and a rotative gear joined to said raising and lowering means and in mesh with the other of said rack gears for simultaneous rotation to lower the wick as said cap is elevated.

2. A safety device for a burner having a fuel spout on its tank, a wick and rotatable wick raising and lowering means comprising a removable cap reciprocably slidable within said spout, rack gears on said cap, a manually rotatable gear meshing with one of said rack gears to effect movement of said cap within said spout, and a rotative gear joined to said raising and lowering means and in mesh with the other of said rack gears to lower said wick simultaneously with said raising of said cap to permit its removal.

3. A safety device for a burner having a fuel spout on its tank and rotatable wick raising and lowering means comprising a rotatable shaft joined to said means, a removable cap reciprocally slidable within said spout, rack gears on opposite sides of said cap engageable with the interior surface of said spout, a manually rotatable gear on said spout and projecting thereinto to mesh with one of said rack gears, and a second rotatable gear on said shaft projecting into said spout and in mesh with said other rack gear.
